ELECTRIC FOOT WARMER

Filed July 8, 1926

INVENTOR
William Wesley Hicks
BY
John Flan
HIS ATTORNEY

UNITED STATES PATENT OFFICE.

WILLIAM WESLEY HICKS, OF SAN FRANCISCO, CALIFORNIA.

ELECTRIC FOOT WARMER.

Application filed July 8, 1926. Serial No. 121,177.

This invention relates to an electrical heating device, and more particularly to one that is adapted to impart heat to the feet of a person, when such a person is sitting 5 or standing.

It is a matter of common observation that when the nether extremities are kept warm, there is a comfortable feeling even when the rest of the body is cooler than normal. In 10 order to take advantage of this, it has been proposed to supply foot warmers, upon which the feet can rest when the user is sitting down; and which can be placed underneath the feet when the user is standing. 15 Such a device is especially useful during these periods of the year when continual artificial heating is inadvisable, while yet certain periods of the day may be otherwise too cool for comfort.

20 It is one of the objects of my invention to provide a simple and inexpensive electrical heater that is especially adapted to perform the functions outlined.

It is another object of my invention to 25 provide a heater that can withstand the ordinary careless handling accorded devices of this character.

My heater is preferably built in the form 30 of a flat plate upon which the feet can rest, and connections lead in at one edge of the plate. These connections form a convenient handle for transporting the device, and if 35 no precautions were taken, they would be readily torn off or loosened. It is accordingly another object of my invention to provide a foot warmer with rugged lead in 40 connections that can be used to transport the device without danger of injury to any of the parts.

45 It is still another object of my invention to provide a foot warmer in which the heat is imparted to the entire outer active surface by conduction from a relatively small heating element, whereby the cost of the element can be maintained at a low value.

50 My invention possesses many other advantages, and has other objects which may be made more easily apparent from a consideration of one embodiment of my invention. 55 For this purpose I have shown a form in the drawings accompanying and forming part of the present specification. I shall now proceed to describe this form in detail, which illustrates the general principles of my invention; but it is to be understood that this detailed description is not to be taken

in a limiting sense, since the scope of my invention is best defined by the appended claim.

Referring to the drawings:

Figure 1 is a sectional view of one embodiment of my invention;

Fig. 2 is an enlarged detail section, illustrating the manner in which the lead-in is constructed;

Fig. 3 is a bottom plan view of the device, on a somewhat reduced scale;

Fig. 4 is a detail, with a portion of the device removed, to disclose the manner in which the apparatus is wired; and

Fig. 5 is a fragmentary view, taken from plane 5—5 of Fig. 1.

The entire heater has a box-like, shallow casing 11, made from thin heat conducting material, such as brass or aluminum. The 75 main surface of this casing forms its upper side, upon which the feet are intended to rest. A thin layer of insulating material 12, such as mica, is placed adjacent the inner surface. While this layer serves efficiently as an electrical insulator, yet it does not interfere with the conduction of heat to the upper surface from a heating element 13. This element may be supported on an insulation block 14, and preferably consists of 80 bare resistance wire which is convoluted on the top surface of said block, and held thereon in any appropriate manner.

The element 13 is preferably placed directly adjacent the layer 12, so as to be in proper 90 heat conducting relation with respect to the central portion of the casing 11. From this central portion, the heat is rapidly conducted to the entire casing 11, although as clearly shown in Fig. 3, the heating unit 95 covers only a small portion of the casing. In this manner, a compact and inexpensive heating unit can be provided.

In order to fill in the rest of the space in 100 casing 11 around the support 14, use is made of a number of insulation blocks, such as 15, 16, and 17, made from asbestos or the like. The outer layer 16 overlies the blocks 14, 15 and 17, and serves also to insulate the heat from the bottom plate 18, serving as a 105 cover. This plate is shown as of metal, fitting rather closely within casing 11, to which if desired it can be soldered. However, I show a plurality of fastening devices, such as flat head bolts 19, which pass 110 through the casing 11 and thread into cover 18 to clamp the various elements in the cas-

ing together. The bolts 19 are spaced near the edge of casing 11, and extend beyond cover 18. On their extensions are fastened crown nuts 20 which serve as feet for the entire warmer. These nuts are preferably made from metal or bakelite, whereby they also serve efficiently to prevent material conduction of heat to the floor; and they also serve as feet for spacing the device from the floor.

The manner in which the connections are led into the heating unit 13 will now be described. For this purpose, I show a steel armored cable 21, entering into the edge of 15 the casing 11 and projecting therein for a considerable distance. The casing 11, as clearly shown in Fig. 5, has a slot 22 cut therein, to permit the cable to enter. Furthermore, the top of casing 11 is cut away 20 in a curve to fit around cable 21, as indicated at 23; and a similar groove 24 is cut in cover 18. Thus the cable 21 is securely clamped between the two grooves when the bolts 19 are fastened down. The entire 25 assembly can be readily transported by grasping cable 21 as a handle, which cable is purposely led into the center of one of the edges of casing 11 so as to keep the assembly balanced when suspended by cable

21, on an axis passing through the cable 30 opening.

The wires 25 from cable 21 are led to a pair of posts 26 and 27, in block 16, projecting into a recess 28 in the lower side of insulation 16. The post 26 can be directly 35 connected to one terminal of the heating unit 13. The other post 27 however is shown as connecting to a fuse link 28', the other end of the link connecting to a post 29 to which also connects the other terminal of 40 unit 13. The cover 18 has a removable plate 30 immediately over recess 28, in order to permit fuse 28 to be renewed when occasion demands.

I claim:

In an electrical foot warmer, a shallow casing of heat conducting material, a cover for the casing, a heating element within the casing, an armored cable extending through a slot in an edge of the casing, the casing 50 and the cover being each formed with a curved seat, cooperating to clamp the cable tightly, whereby it can be used as a handle for the device.

In testimony whereof I have hereunto set 55 my hand.

WILLIAM WESLEY HICKS.
